THREAD MEASURING DEVICE

Pieter K. Noordenbos, Ede, and Egbert H. Boiten, Ellecom, Netherlands, assignors to American Enka Corporation, Enka, N.C., a corporation of Delaware

Filed Apr. 3, 1963, Ser. No. 270,449

Claims priority, application Netherlands Apr. 5, 1962

5 Claims. (Cl. 235—61)

This invention relates to means for measuring the length of a yarn or thread while it is being wound into package form.

In certain instances it becomes highly desirable in textile manufacturing to know exactly the length of thread wound on a particular thread package. Of course it is possible to wind a package of predetermined dimensions and to use this as a basis for computing length of the yarn forming the package but because of variations in denier and tension during winding this computation can give only a rough approximation.

In the prior art various mechanical methods of accomplishing this measurement have been used but they have proved to be cumbersome and complicated to build and operate.

It is therefore an object of this invention to provide a simple, inexpensive, electrically operated measuring device easily adaptable to variations in denier and tension of thread which may be attached to an existing winding apparatus to provide a highly accurate means of measuring the amount of thread wound thereon.

Other objects and advantages of this invention will be apparent upon consideration of the following detailed description of a preferred embodiment thereof in conjunction with the annexed drawings wherein:

FIGURE 1 is a perspective view of a conventional type thread winding apparatus with one form of the measuring device of this invention attached;

FIGURE 2 is a diagrammatic view in side elevation of a thread winding apparatus with a preferred embodiment of this invention attached;

FIGURE 3 is a side elevation of the disk of this invention shown in cross section;

FIGURE 4 is a plan view of an electrical contact disk of this invention;

FIGURE 5 is a plan view of an alternative form of electrical contact disk of this invention;

FIGURE 6 is a plan view of an optical alternative of the disk of this invention;

FIGURE 7 is a side view in cross section along line 7—7 of FIGURE 6.

Referring now in greater detail to FIGURE 1, the thread winding apparatus 10 is pivoted about a shaft 12 and biased by a counter weight 14 to hold the thread guide 16 against the thread package 18. As the thread 20 is wound on the thread package 18 the thread guide 16 traverses back and forth on the traverse mechanism 22 to lay down even convolutions of thread powered by means that are now shown in FIGURE 1 and are not a part of this invention. The thread package 18 is supported on a spindle shaft 24 which is rotated by external means not shown in FIGURE 1 and also not a part of this invention. The disk 26 of this invention is secured to the shaft 24 by the hub 28 and the set screw 30 (see FIGURE 2). The disk 26 as shown in FIGURE 1 is an optical alternative form which is shown for illustrative purposes and it is to be understood that any one of the disks shown in FIGURES 4, 5 and 6 could be used equally well with suitable accessories. The detailed operation of this optical alternate form will now be discussed in detail.

An elongated light source 32 is placed in stationary position on one side of the disk 26. As the shaft 24

2

and the thread package 18 revolve, the disk 26 of an opaque material such as metal with transparent portions such as open slots, is revolved also, bringing one of the open slots 34 (see FIGURE 6) into alignment with the path of the light emitting from the light source 32. This elongated light source may be a standard tubular-shaped incandescent lamp properly shielded to direct the light toward the photocell 36 and is supplied with current from the power source through the wires 33. As this light passes through any one of the slots 34, which is in alignment with the light source 32, it strikes the photocell 36 causing the photocell to close a microswitch to complete the circuit across the wires 38. Thus there is a flow of current from the power source through the switch of the photocell to the registering counter 40. This counter is a dial reading solenoid actuated type which registers one number higher each time the circuit to it is completed.

Thus, as the shaft 24 and the thread package 18 are rotated to wind the thread 20 onto the package, the disk 24 is rotated and as the slots 34 allow the light path to the photocell 36 to be completed the circuit to the counter 40 is closed to actuate the counter. As shown more clearly in FIGURE 6 some of the slots 34 are longer than others and thus as the thread package 18 grows larger the thread winding apparatus 10, as it pivots about the shaft 12, swings the photocell 36 radially outward on the disk 26. This radial movement of the photocell causes it to become aligned with an increasing number of the slots 34 as it swings outwardly because there are a greater number of slot openings along the periphery of the disk than near the center. Thus, as the thread package circumference grows larger, requiring a longer length of thread for each convolution, the circuit to the counter 40 is completed more frequently to accurately register the length of thread on the package at any particular moment as it is wound.

Similarly, an electrical contact version of this invention is illustrated diagrammatically in FIGURE 2. The shaft 24 rotates the thread package 18 along with the disk 26 as previously described. The thread traverse mechanism 22 as part of the winding apparatus 10 pivots outwardly from the thread package as the size of the package grows. As previously described, it pivots about shaft 12, not shown in FIGURE 2. As the mechanism 22 swings outwardly from the thread package it carries a contact brush 42 radially outwardly along the surface of the disk 26 in a pattern similar to that followed by the photocell 36 in FIGURE 1. The disk 26 of this electrical contact embodiment is made of an insulating material such as hard rubber or Bakelite and has a plurality of lines of conductive material on the surface that faces the contact brush 42. The configuration of these conductive lines is clearly shown in FIGURE 4, with some of the lines being longer than others and running in a radial direction from the periphery of the disk 26 toward the center. Thus as the contact brush 42 moves radially outwardly along the surface of the disk 26, as the size of the thread package 18 grows, it contacts an increasing number of these conductive lines. The counter 40 is actuated each time one of these conductive lines touches the contact brush 42. In this embodiment the power source for the counter 40 is of low voltage such as a dry cell battery 44. The negative terminal of the battery is grounded to the frame of the thread winding machine of which the traverse mechanism 22 is a part and the positive terminal of the battery is connected directly to the counter 40.

As the disk 26 is rotated the brush 42 comes in contact with each conductive line 46 (see FIGURE 3) as it passes under the brush. This conductive line may be recessed into the insulating material 48 as shown in FIG-

URE 3 or may be a very thin surface layer so long as it forms a smooth surface on the disk and is connected to the metal backing 50 and the metal hub 28 of the disk 26. Thus there is a completed electrical circuit from the brush 42 through the foregoing metal parts to the shaft 24 and through the metal frame of the machine back to the negative side of the battery.

As previously explained when referring to the slots of the optical disk, the conductive lines 46 of the preferred electrical contact disk are also of varying length extending from the periphery of the disk 26 toward the center so that there are an increasing number of contact points with the brush 42 as the package size grows and the brush 42 swings radially outwardly on the disk 26.

FIGURE 5 illustrates an alternative form of electrical disk where the conductive lines are arranged in a spiral pattern. By following the dot-dash concentric circles 52 which represent imaginary paths which the contact brush would follow on either FIGURE 4 or FIGURE 5, it is apparent that there is a larger number of points of contact on each larger concentric circle.

It is necessary that a different measuring disk be used for each different denier of thread to be wound on a specific thread package and to this end the disks are designed to be easily replaceable by loosening the setscrew 30 and sliding the disk 26 off the end of the shaft 24. The particular line or slot pattern needed for a given denier of thread and package size may be calculated mathematically or it may be easily determined experimentally by one skilled in the art. After the required line pattern has been determined the disk may easily be made by coating the insulating portion with copper foil and then etching away the unneeded portion by processes which are well known in the art.

Although the foregoing description has been concerned with a preferred embodiment of this invention, it is to be understood that other alternatives within the scope of the principles herein applied are also contemplated. For instance, it is contemplated that the disk may have electrical resistance varying in radial direction and a tachodynamo coupled to the spindle shaft. A watt-hour meter may then be used to record the electrical energy produced by a circuit through the brush member and rotatable disk.

In another possible embodiment the traverse mechanism supports a magnetic eraser, a writing head and a reading head, which are positioned in this order one after another in tangential direction and opposite to the disk, the disk being provided with a magnetizable layer, and the reading head being coupled with its output both to the exciter of the writing head and to a counting mechanism for registering electric impulses.

Every time the reading head reads a signal registered on the magnetizable layer by the writing head and transmits it to the counting mechanism, the writing head registers a new signal on the magnetizable layer.

Consequently, the distance between the signals read are always equal to the constant distance between the writing head and the reading head. This implies that the counter actually detects a number of equally great distances, which

are each in a constant proportion to the thread lengths wound in equal time intervals.

In another embodiment according to the invention the change in the radius of the package is not followed continuously by the measuring member, but is measured stepwise.

We claim:

1. In winding apparatus including a drive shaft for rotating a package support and a traverse mechanism that follows the outward growth of the package as successive convolutions are wound on said support the improvement that comprises a counter, an electric circuit for activating said counter when said circuit is actuated, said circuit including disk borne means rotatable with said shaft cooperating with an element borne by and moveable with said traverse mechanism for actuating said circuit.

2. In winding apparatus including a drive shaft for rotating a yarn package support and a traverse mechanism that follows the outward growth of the yarn package as successive convolutions are wound on said support the improvement that comprises a counter, an electric circuit for activating said counter when said circuit is actuated, said circuit including a disk containing a plurality of conductive elements rotatable with said shaft and a brush moveable with said traverse mechanism to contact varying conductive elements as the size of said yarn package grows.

3. The device of claim 2 wherein the conductive elements of said disk extend radially inwardly from the periphery of the disk, some of said elements being radially longer than others whereby said brush contacts an increasing number of elements as it moves radially outwardly on said disk.

4. The device of claim 2 wherein the conductive elements of said disk follow a spiraled path away from the center of the disk whereby said brush contacts said elements with increasing frequency as it moves radially outwardly on said disk.

5. In winding apparatus including a drive shaft for rotating a yarn package support and a traverse mechanism that follows the outward growth of the yarn package as successive convolutions are wound on said support the improvement that comprises a counter, an electric circuit for activating said counter when said circuit is actuated, said circuit including a disk with portions of different transparency rotatable with said shaft, a light source element on one side of said disk, a photocell element on the other side of said disk, one of said elements being moveable with said traverse mechanism to scan said disk at different radii thereof whereby to transmit varying amounts of light to said photocell as the size of said yarn package grows.
